UNITED STATES PATENT OFFICE.

COMMANDER P. BAKER, OF ST. CATHERINE, MISSOURI.

DEVICE FOR BINDING FODDER.

1,076,403.

Specification of Letters Patent.

Patented Oct. 21, 1913.

Application filed February 7, 1913. Serial No. 746,896.

To all whom it may concern:

Be it known that I, COMMANDER P. BAKER, a citizen of the United States, residing at St. Catherine, in the county of Linn and State of Missouri, have invented new and useful Improvements in Devices for Binding Fodder, of which the following is a specification.

This invention relates to an improved device for binding or bundling corn fodder and the like, and it has for its object to produce a simple and convenient device which may be readily applied to and used in connection with an ordinary wagon box for the purpose set forth.

A further object of the invention is to produce a device of the class described which may be conveniently adjusted to wagon boxes of different height and which may also be adjusted so as to be effectively used for bundling fodder of varying lengths.

A further object of the invention is to construct a device of the character described which, while in position on a wagon box, may be conveniently folded and supported for transportation while the wagon is moving from one place to another.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the claims may be resorted to when desired.

In the drawings, Figure 1 is a side elevation showing a portion of a wagon upon which the improved device has been mounted for operation. Fig. 2 is a vertical sectional view taken on the line 2—2 in Fig. 1. Fig. 3 is a side view showing a bundle of fodder in position. Fig. 4 is a top plan view showing a bundle of fodder in position to be tied. Fig. 5 is an end view showing the device folded for transportation.

Corresponding parts in the several figures are denoted by like characters of reference.

A pair of vertical frame bars 1, 1 are provided at their upper ends with cleats 2

adapted to be hooked over the sideboards 3 of an ordinary wagon box. Each of the frame bars is provided with laterally extending arms 3' overlapping each other and connected slidably together by means of sleeves or bands 4 having tightening means, such as set screws 5, whereby the overlapping arms may be secured with respect to each other, thereby enabling the frame bars 1, 1 to be moved together or apart, as desired, and secured in adjusted position.

Connected with the lower ends of the frame bars 1 by means of hinges 6 are bracket members 7, and connected hingedly with the outer ends of said bracket members are legs or supports 8 which are adapted to fold against the bracket members when the latter are folded upwardly adjacent to the frame bars 1. The bracket members may be supported in folded relation with respect to the frame bars by means of hooks 9 and eyes or keepers 10. The legs or supporting members are provided with extensions 11 which are slidably or telescopically connected therewith by means of sleeves 12 having fastening means such as set screws 13.

A sleeve 14 which is slidably mounted on the lowermost pair of overlapping arms 3' is provided with eyes 15, 16, one above the other. Connected with the lower eye 16 is one end of a tightening rope 17, said rope being guided over a pulley 18 in a loose block 19 having a hook 20 with which it may be detachably connected with the eye 15 above the eye with which the rope 17 is connected. A flat spring 21 which will serve on occasion to hold the free end of the tightening rope 17 while the bundle is being tied is secured on the outer side face of one of the bracket members 7. A twine can 22 is provided which may be detachably supported on a pair of overlapping arms 3.

In the operation of this invention, the improved device is mounted on one of the sides of an ordinary wagon box. The extension members 11 are so adjusted with respect to the legs of supporting members 8 that when the bracket members 7 are folded outward from the frame members 1, 1 they may be supported in an approximately horizontal position by the lower ends of the extension members resting on the ground. The frame bars 1, 1 are also moved together or apart as may be required, and secured in adjusted position by the sleeves 4 and set screws 5, according to the

length of the fodder that is to be operated. When the wagon has been brought to the desired position, the fodder may be piled on the brackets 7 until a sufficient quantity 5 to form a bundle has been placed in position, the tightening rope 17 being meanwhile permitted to depend between the bundle and the wagon box. When the desired quantity has been accumulated the 10 pulley block is lifted and connected by the hook 20 with the eye 15, thus bringing the tightening rope around the bundle which may now, by pulling the tightening rope, be tightened to a compact condition in 15 which it may be held by engaging the tightening rope beneath the holding spring 21. The bundle may now be tied with twine supplied from the can 22, after which the rope 17 is cast loose, and the bundle may 20 now be thrown into the wagon box, after which the device is ready for a repetition of the operation. While the wagon is being transported from one place to another, the bracket members 7 may be folded upward 25 adjacent to the frame members 1 and supported in this position by engaging the hooks 9 with the eyes 10. The supporting members 8 will now be supported adjacent to the outer faces of the bracket members 30 in an elevated position with respect to the ground, and the wagon may now be moved to another location.

Having thus described the invention, what is claimed as new, is:—

35 1. A frame structure comprising side members having laterally extending overlapping arms, means for adjustably connecting the arms, supporting hooks at the upper ends of the side members, supporting brackets connected hingedly with the lower ends of the side members, and leg members connected hingedly with the bracket members.

40 2. A supporting frame having adjustably connected side members, bracket members connected hingedly with the lower ends of the side members, leg members connected hingedly with the bracket members, and means for supporting the bracket members 50 in raised condition with respect to the frame members.

45 3. A frame having means whereby it may be supported on a wagon box, said frame including side members having overlapping arms and means whereby said arms are adjustably connected, bracket members connected hingedly with the lower ends of the side members of the frame, leg members connected hingedly with the bracket members, extension members connected adjustably with the leg members, and means 55

whereby the bracket members may be supported in folded condition with respect to the side members of the frame.

4. A frame comprising side members having overlapping arms, and means whereby said arms are adjustably connected, said side members having supporting hooks at their upper ends, bracket members connected hingedly with the lower ends of the side members, means for supporting said bracket members in approximately a horizontal position approximately at right angles to the side members of the frame, a tightening rope having one end connected with the frame, a loose block having a pulley over which the tightening rope is guided, and means for connecting the block detachably with the frame.

5. A frame comprising side members having overlapping arms, and means whereby said arms are adjustably connected, said side members having supporting hooks at their upper ends, bracket members connected hingedly with the lower ends of the side members, means for supporting said bracket members in approximately a horizontal position approximately at right angles to the side members of the frame, a tightening rope having one end connected with the frame, a loose block having a pulley over which the tightening rope is guided, and means for connecting the block detachably with the frame; and means on one of the bracket members whereby the free end of the tightening rope may be secured.

6. A frame comprising side members having laterally extending overlapping arms and provided with supporting hooks at their upper ends, means whereby the overlapping arms are adjustably connected to secure the side members at various distances apart, a sleeve slidably engaging one pair of overlapping arms and having eyes associated therewith, a tightening rope connected with one eye of the sleeve, a loose block having a pulley over which the tightening rope is guided, said block having a hook adapted to detachably engage the other eye of the sleeve, bracket members connected hingedly with the lower ends of the side members of the frame, one of said bracket members having a holding spring, and leg members connected hingedly with the bracket members to support the latter in extended position.

In testimony whereof I affix my signature in presence of two witnesses.

COMMADORE P. BAKER.
